UNITED STATES PATENT OFFICE.

FRED O. STOKKE, OF MINNEAPOLIS, MINNESOTA.

AUTOMATIC LOADING PISTOL.

1,407,959.

Specification of Letters Patent. Patented Feb. 28, 1922.

Application filed June 11, 1920. Serial No. 388,334.

To all whom it may concern:

Be it known that I, FRED O. STOKKE, a citizen of the United States, residing at Minneapolis, in the county of Hennepin and

5 State of Minnesota, have invented certain new and useful Improvements in Automatic Loading Pistols, of which the following is a specification.

This invention relates to fire arms and 10 is an improvement on my automatic pistol filed November 30, 1917, Serial No. 204,693, and the primary object of the invention is to simplify the construction of the pistol and to provide an improved frame, which 15 can be readily and quickly taken down by the ordinary layman to expose the working parts thereof, to permit of the cleaning and the replacing of the parts when necessary, without the use of tools.

20 Another object of the invention is to provide an automatic pistol in which the frame thereof embodies a minimum number of parts which are associated with one another in such a manner as to permit the smooth 25 operation of the gun with a minimum amount of wear on the parts thereof and a maximum amount of safety for the user.

A further object of the invention is to provide an improved means for mounting 30 the ejector in position, so as to not require the use of fastening elements and which will absolutely preclude movement thereof when the pistol is in use, and which will permit of the replacing of the ejector when worn.

35 A further object of the invention is to provide a single element carried by the hand grip frame for holding the handle plate against movement, the pivoted catch for the magazine in position, and the 40 removable plates for the hand grip against displacement.

A still further object of the invention is to provide an improved automatic pistol of the above character which is durable and 45 efficient in use, one that is simple and easy to manufacture, and one which can be placed upon the market at a reasonable cost.

With these and other objects in view, the 50 invention consists in the novel construction, arrangement and formation of parts, as will be hereinafter more specifically described, claimed and illustrated in the accompanying drawings, forming a part of this specification, in which drawings:

55 Figure 1 is a side elevation of the improved pistol.

Figure 2 is a longitudinal section through the same, showing parts thereof in elevation, the hammer being in cocked position ready for firing.

60 Figure 3 is a side elevation of the pistol with the side plate and hand grip plate removed disclosing the operating parts of the pistol, the breech block being shown in its rearward position for cocking the hammer, parts of the pistol being shown in section.

Figure 4 is a side elevation of the hand grip frame showing the operating parts in position for firing, the side plate and the 70 hand grip plates being removed.

Figure 5 is a detail side elevation of the breech block.

Figure 6 is a detail side elevation of the 75 top frame and barrel.

Figure 7 is a detail side elevation of the side plate.

Figure 8 is a detail perspective view of the same showing the safety catch carried thereby.

80 Figure 9 is a detail elevation of the magazine.

Figure 10 is a detail side elevation of one of the hand grip plates.

Figure 11 is a detail longitudinal section 85 through the breech part of the pistol, illustrating the extractor and ejector.

Figure 12 is a detail horizontal cross section through the hand grip frame showing the grip plates in position thereon, the magazine being removed from the handle.

Figure 13 is a detail fragmentary vertical section through the breech part of the pistol, and,

Figure 14 is a detail perspective view of 95 the inner end of the barrel, showing the ejector carried thereby.

Referring to the drawings, in detail, wherein similar reference characters designate corresponding parts throughout the 100 several views, the letter A generally indicates the improved pistol, the frame of which consists of two essential parts, namely the hand grip frame 15 and the top frame 16, which carries the barrel 17.

105 The hand grip frame 15 includes the longitudinally extending side wall 18 and the depending downwardly extending handle frame 19, which projects laterally from the lower edge of the side wall 18. The handle frame 19 includes the front and rear walls 20 and 21 and the integral side plate 22,

which terminates short of the side wall 18. The inner surfaces of the front and rear walls 20 and 21 are provided adjacent to one side face thereof with grooves 23, which 5 slidably receive the removable side plate 24. The side plate 24 ends short of the top edges of the front and rear walls 20 and 21 as clearly shown in Figures 3 and 4 of the drawings. The side plates 22 and 24 form 10 means for receiving the fastening screws 25 which detachably hold the hand grip plates 26 in position. The hand grip plates 26 are shaped to conform to the configuration of the handle frame 19 and have their outer 15 surfaces serrated so as to permit a firm grip to be obtained on the pistol by the hand of the user. The fastening screws 25 extend through the hand grip plates 26 into the upper ends of the side plates 22 and 24 20 and these plates are provided with suitable internally threaded openings 27 for the reception of the same. The upper end of the rear wall 21 supports the rearwardly extending lower wall 28, which extends laterally from the side wall 18 and this wall is 25 provided with a grooved upwardly extending rear wall 29 which terminates short of the end block 30, carried by the upper edge of the side wall 18. The upper end of the front 30 wall 20 carries the forwardly projecting trigger guard 31, the sides of which are reduced in thickness for the reception of portions of the top frame 16 which will be now described.

35 The top frame 16 includes a body 32, which is provided with a substantially polygonal shaped longitudinally extending groove 33 for the reception of the squared portion 34 of the barrel 17. The body 32 40 is provided with a pair of depending parallel spaced flanges 35, which engage on opposite sides of the reduced portion of the trigger guard 31 and these flanges have registering openings 36 which are adapted to 45 register with an opening 37 formed in the trigger guard 31 when the frame sections 15 and 16 are in assembled position. These registering openings are adapted to receive a removable thumb screw 38 which is 50 tapered toward one end so as to facilitate the positioning thereof in the pair of openings. The body 32 has integrally formed therewith the rearwardly extending top wall or plate 39, the free end of which is provided with 55 a bevelled tongue 40 which is adapted to fit in a notch 41 formed in the upper portion of the forward face of the end block 30.

One face of the squared portion 34 of the barrel 17 is notched as at 42 for the reception 60 of the base plate 43 of the ejector 44. The outer surface of the base plate 43 extends flush with the squared portion 34 of the barrel 17 and carries the rearwardly extending rod 45 the free terminal of which 65 carries a hooked end 46. The inner surface of the body 32 is recessed as at 47 for the reception of the inner end of the rod 45. The lower forward face of the squared portion of the barrel is provided with a plurality of depending teeth 48, which are 70 adapted to engage teeth 49 cut in the upper surface of the trigger guard 31. These teeth 48 and 49 absolutely preclude any movement of the barrel in relation to the trigger guard when the portions of the frame 75 are in their assembled position. The upper surface of the rear wall 28 and the lower edge of the end block 30 are provided with grooves 50, which slidably receive the side plate 51, which extends in parallel relation 80 to the side plate or wall 18 and this side plate or wall 51 is shaped to conform to the configuration of the side wall or plate 18. The groove formed in the end block 30 terminates short of the rear end of the block 85 and this prevents rearward movement of the side plate or wall 51 and when the top frame 16 is in position the flanges 35 thereof engage the forward edge of the side plate and prevent forward movement thereof. One 90 of the depending flanges 35 is provided with a cut out portion which is adapted to receive the forwardly projecting tongue 52 formed on the side plate 51. The provision of this tongue provides for a tight fit between the portions of the frame.

The space between the side plates or walls 18 and 51 and the top plate 39 is adapted to 95 slidably receive the breech block 53 and the same is provided with rearwardly extending 100 side walls 54, which are adapted to slidably engage the outer surfaces of the end block 30 when the breech block is moved to its rearmost position. The outer surfaces of the breech block are provided with suitable corrugations to permit a firm grip to be had on the same by the user of the pistol. The breech block 53 carries the rearwardly extending bolt 55 and the bolt and breech block 105 are slotted to receive the firing pin 56, which has coiled around the same intermediate its ends the rebound spring 57 which is fitted in a suitable opening 58 formed in the breech block. The firing pin extends slightly beyond the bolt 55 so as to permit of the same 110 being engaged by the hammer 58 which is arranged between the side plates or walls 18 and 51 and extends through the space between the end blocks 30 and the rear wall 29. The bolt 55 can be formed integral with the 115 breech block 53 or the same can be detachably connected thereto in any preferred manner and as shown the breech block is provided with an internally threaded socket for the reception of the threaded end of the bolt. The end block 30 is provided with an aperture 59 for the reception of the bolt and the same is adapted to extend through the aperture to engage the hammer 58 to move the 120 same to a cocked or safety position. The for- 125

130

ward portion of this aperture 59 is enlarged as at 60 for the reception of the recoil spring 61 which is coiled around the bolt and is confined between the breech block 53 and the 5 shoulder formed by the enlarged portion of the bore of the opening 60. The barrel 17 can be formed of any desired length and the same is provided adjacent to the squared portion 34 thereof with a gradually tapered 10 annular shoulder 62 which is adapted to engage the forward surface of the upper frame 16 and the trigger guard 31.

The lower end of the rear wall 21 of the handle frame 19 is provided with a transversely extending recess, which is adapted to receive a pin 63 and this pin 63 engages the flange formed on the side plate 24 to hold the same against accidental displacement from the handle. The terminals of this pin 20 project outwardly beyond the side faces of the rear wall 21 and are adapted to be positioned in suitable sockets 64 provided in the inner surfaces of the hand grip plates 26 and this pin effectively prevents twisting movement 25 of the hand grip plates on the screws 25 as a pivot. This pin 63 further acts as a pivot pin for the retaining latch 65 of the magazine 66, which has been described in detail in the pending application. The latch 30 65 is provided with a hooked end 66' which is adapted to engage the lower end of the magazine and hold the same against displacement. This hooked end 66' is serrated so as to permit a firm grip to be obtained 35 thereon by the thumb of the user. A coiled spring 67 is provided for normally urging the hooked end 66' into engagement with the magazine. Thus it will be seen that the pin 63 performs a three fold function, namely, 40 a pivot pin for the latch 65, a retaining pin for the side plate 24, and a means for preventing the twisting of the hand grip plates 26.

The inner surface of the side wall or plate 45 18 is provided adjacent to its rear end with integral inwardly extending spaced pivot pins 68 and 69, which form respectively pivots for the hammer 58 and the sear 70. The hub of the hammer 58 is provided with a 50 relatively deep notch 71 which forms the safety or half cock for the hammer and a relatively shallow notch 72 which forms the full cock for the hammer. The sear 70 is provided with a rearwardly extending terminal 73 which is adapted to engage in either of the notches. The sear is normally moved into engagement with the hub of the hammer by means of an expansion coiled spring 73' which is confined between an inwardly extending lug 74 formed on the side wall or plate 18 and against an extension 75 formed on the sear. The forward end of the frame 15 is provided with a cut out portion which receives the upper end of the 65 trigger 76 and this cut out portion is pro-

vided with an integral pivot pin 77 therefor. The trigger 76 is pivotally connected to the trigger bar 78, and the inner surface of the side wall or plate 18 is recessed to receive the same and this trigger bar fits flush 70 with the inner surface of the plate or wall 18. The upper edge of the trigger bar 78 is provided with an extension 79 which is adapted to be engaged by the breech block when the same is moved rearwardly for moving 75 the rearwardly extending portion 80 of the trigger bar out of engagement with the sear 70, so as to prevent the accidental firing of a cartridge while the same is being forced into position in the bore of the barrel 17. 80 The trigger 76 is normally urged to a forward position by means of an expansion coiled spring 81 which is fitted in a suitable recess provided in the frame for that purpose. The upper end of the rear of the handle frame carries a lug 82 which is recessed to slidably receive the hammer pin 83 and this hammer pin has coiled around the same the expansion spring 84 which is adapted to normally urge the hammer to 85 toward the firing pin. The pin 83 is provided with a head 85 which engages the hammer below the pivot pin 68. The lug 82 also provides a support for an expansion coiled spring 84', which engages the trigger 90 bar and normally urges the same into engagement with the sear 70. The side plate 51 is provided with a recess 88 which receives the safety catch member 89, which is adapted to be moved into the path of the 100 breech block 53 when the last cartridge has been fired. This safety catch 89 includes the flat plate 90, the forward end of which is pivotally mounted upon an integral pin 91 which is formed on the side wall or plate 105 51. The upper edge of the plate is provided with an upwardly extending lug 92. The forward end of the plate 90 is provided with a depending extension 94, which carries the outwardly extending operating knob 95 110 115 which is slidably mounted in a notch 96 formed in the side plate. The lug 92 is adapted to be moved into the path of the breech block 53, when the same has been moved to its rearmost position by the explosion of the last cartridge, by the cartridge follower 97 which is normally urged upwardly in the magazine by the expansion coil spring 98. The follower 97 is provided with outwardly extending knobs 99, which are slidably mounted in longitudinally extending slots 100 formed in the side walls of the magazine. These knobs 99 are adapted to facilitate the movement of the follower to the lower end of the magazine when it is 120 125 desired to refill the magazine with cartridges. The inner surface of the side wall or plate 51 is provided with a groove 101 which is adapted to receive the follower 97 and when the last cartridge is expended from 130

the magazine it will be seen that one of the knobs 99 will move upward in the groove 101 and engage the plate 89 and move the lug 92 upwardly. This effectively prevents the 5 movement of the breech block back to its normal position when the last cartridge has been expended, thereby effectively calling the attention of the user of the pistol when all of the cartridges have been fired. The 10 breech block can be readily returned to its normal position by pushing down the knob 95 which will move the lug 92 below the path of the breech block against the tension of the magazine spring 98.

15 The forward end of the breech block 53 is provided with a recess 103 which supports a pivot pin 104 on which is pivotally mounted the extractor 105. The extractor 105 is provided with a hooked terminal which 20 is adapted to engage the rim of a cartridge when the same is positioned in the bore of the barrel and a notch 106 is formed in the barrel for the reception of the hooked end. The hooked end of the extractor 105 is normally held in engagement with the cartridge 25 by means of an expansion coil spring 107. It can be seen that when the breech block is moved rearwardly by the explosion of the cartridge, the extractor 105 will engage 30 the cartridge and pull the same rearwardly and when the cartridge engages the hooked end 46 of the rod of the ejector 44 the cartridge will be thrown sidewise out of the piston. The ejector 44 is held against accidental movement and displacement from engagement with the barrel and top frame 16 by the side wall or plate 18 which is notched 35 as at 108 for engagement with the same.

From the foregoing description of the 40 drawings, it can be seen that an exceptionally simple frame is provided and it is merely necessary to loosen and remove the thumb screw 38 when it is desired to take down the frame of the pistol to expose the 45 parts to view, when it is desired to clean or repair the pistol. After the thumb screw 38 has been removed, pressure is applied to the forward end of the barrel which moves the teeth 48 out of engagement with the 50 teeth 49 and swings the frame on the tongue 40 as a pivot and a sliding forward movement of the frame 16 moves the tongue 40 out of engagement with the notch 41. The side plate or wall 51 can then be slid out 55 of engagement with the handle frame 15 which completely exposes all of the working parts of the pistol to view. The breech block can also be readily removed by sliding the same forwardly on the frame 15.

60 If it is desired to remove the barrel from the top frame 16, the frame 16 is grasped in one hand while the barrel is grasped in the other and pressure is applied thereto, which will effectively separate the barrel and 65 frame.

The pistol is operated similar to the pistol in my pending application and the magazine is filled with cartridges in the same manner and pushed in the handle frame, and when it is desired to fire the gun the 70 opposite sides of the breech block are grasped by the hands of the user and the same is moved rearwardly which forces the bolt 55 in engagement with the hammer 58 and swings the same on its pivot 68 and 75 moves the same to its cocked position. The returning movement of the breech block engages a cartridge and pushes the same in the barrel. The pistol is then ready for firing, and when pressure is applied to the trigger 80 76 the trigger bar 78 will be moved rearwardly which will operate the sear to release the hammer 58. The hammer 58 will forcibly engage the firing pin 56 and move the same into engagement with the rim of 85 the cartridge and thus explode the firing cap. When a cartridge is fired the breech block will be thrown back by the force of the explosion and the loading will take place automatically. When it is desired to carry 90 the gun in a safety position the breech block is slid partially to its rearward position which will move the trigger bar 78 downwardly below the path of the sear and when the sear engages in the relatively deep notch 95 71 the same will be moved from out of engagement with the trigger bar and thus prevented from operation. When the hammer is moved to its cocked position the sear engages in the relatively shallow notch and 100 permits the trigger bar to readily engage the sear.

Changes in detail may be made without departing from the spirit of this invention; 105 but,

I claim:

1. In an automatic pistol, a casing including a lower hand grip frame having an end block, a top frame including a body, and a top wall carried by the body and arranged to engage the end block, depending flanges carried by the body and arranged to engage the hand grip frame, a barrel detachably carried by the top frame and arranged to be held in position by the hand grip frame when the frames are in assembled position, and means extending through the depending flanges and the hand grip frame to hold the frames in assembled position.

2. In an automatic pistol, a casing including a lower hand grip frame having an end block, a top frame including a body and a top wall carried by the body and arranged to engage the end block, depending flanges carried by the body and arranged to engage the hand grip frame, a barrel detachably carried by the top frame and arranged to be held in position by the hand grip frame when the frames are in assembled position, means extending through the depending 120 flanges and the hand grip frame to hold the frames in assembled position.

125

130

- flanges and the hand grip frame to hold the frames in assembled positions, and a breech block confined between the lower frame and said end block thereof, and the top wall 5 and body of the top frame.
3. In an automatic pistol, a hand grip frame including a side wall, a depending open handle carried by the side wall, an end block, and a trigger guard, a top frame 10 including a body, an upper wall, and depending side flanges carried by the body and arranged to engage the trigger guard when the frames are in assembled position, a side wall removably carried by the hand 15 grip frame and adapted to be held against movement by the top frame, when the frames are in assembled position, and detachable means arranged to removably hold the frames in assembled position.
4. In an automatic pistol, a casing including a hand grip frame having a side wall, a depending open handle frame, an end block, and a trigger guard, a top frame including a body, a rearwardly extending top wall 20 arranged to pivotally engage the end block, depending side flanges carried by the body and arranged to engage the opposite sides of the trigger guard, a side plate arranged in parallel relation to the side wall and re- 25 movably carried by the hand grip frame and arranged to engage the body of the top frame when the frames are in assembled position, a breech block slidably mounted between the hand grip frame and end block 30 thereof and the body and top wall of the top frame, and a removable fastening element extending through the side flanges and trigger guard and arranged to hold the frames in assembled position.
5. In an automatic pistol, a casing including a hand grip frame having a side wall, a depending laterally extending handle frame carried by the side wall, an upwardly extending end block carried by the rear end 35 of the side wall, a forwardly extending trigger guard carried by the forward end of the hand grip frame, a top frame including a body, a rearwardly extending top wall carried by the body, depending flanges 40 carried by the body and arranged to engage the opposite sides of the trigger guard, a barrel detachably carried by the body, teeth formed on the lower surface of the barrel adjacent to the rear end thereof, teeth formed 45 on the upper edge of said trigger guard arranged to engage the teeth on said barrel 50 when the frames are in assembled position, a removable side plate slidably carried by the hand grip frame and adapted to be held against movement by the top frame when the frames are in their assembled position, a breech block slidably mounted between the hand grip frame and the top frame, and a single removable fastening element extend- 55 ed through the side flanges and the trigger guard frame. 60
6. In an automatic pistol, a top frame including a body having a longitudinally extending slot formed therein, a barrel having a polygonal shaped rear end fitted in said slot, one face of said polygonal end of the barrel having a recess therein, an ejector including a flat plate detachably fitted in said recess and arranged to be engaged by said body. 65
7. In an automatic pistol, a top frame including a body having a longitudinally extending slot, a barrel having a rearwardly extending shank polygonal shaped in cross section detachably fitted in said slot, one face of the polygonal shank having a recess therein, an ejector including a shank having a hooked terminal and a flat plate fitted in said recess and engaging the inner surface of the body, a hand grip frame arranged to engage the rear edge of the flat plate of the ejector when the frames are in assembled position, and means for holding the frames in assembled position. 70
8. In an automatic pistol, a handle including a rear wall, an integral side wall, a removable side wall slidably carried by the rear wall, detachable hand grip plates carried by the opposite sides of the handle and a pin carried by the rear wall and arranged 75 to engage the side wall and the hand grip plates to hold the same against movement. 90
9. In an automatic pistol, an open handle frame including a front and a rear wall, an integral connecting side wall, a removable side wall slidably carried by the front and rear walls, a magazine arranged to be received in the handle, a catch carried by the rear wall and arranged to detachably engage the magazine to hold the same against movement, side grip plates carried by the handle and a transversely extending pin arranged to pivotally support the catch, and engage the removable side plate and hand grip plates to hold the same against move- 100
- 105
